ELECTRICAL CONNECTOR

Waldo A. Saul, Lexington, and Jack J. Staller,
Waltham, Mass., assignors to Raytheon Manufacturing Company, Newton, Mass., a corporation of Delaware

Application September 21, 1951, Serial No. 247,602

3 Claims. (Cl. 339—75)

1

This invention relates to electrical connectors and more particularly to the type that permits initial contact to be made under slight pressure with full contact pressure applied after the initial contact is made.

In electrical connectors, it is desirable to have both the best possible electrical contact and the greatest possible ease in connecting and disconnecting the conductors. With demountable connectors the contact is usually obtained by spring pressure; the greater the pressure the greater is the electrical contact, but the greater the pressure the greater is the amount of force required to make and break the connection with a consequent increase in the risks of damage to the equipment being connected. If the parts could be physically brought into contact position under light pressure and then the pressure increased to insure good electrical contact, and the pressure released before disconnecting, the desired high pressure at the contacting surfaces necessary for good electrical conductivity could be obtained while the current is flowing through the connector, while at the same time this greater pressure could be reduced while the connection was being made or broken to avoid the necessity for using great force during these operations.

This is accomplished in the present invention by providing a rotatable eccentric cam shaft designed to apply pressure to the contact elements when the shaft is in one position and no pressure when in another position. A lock is also provided to bring the conductors together as the shaft is rotated from the release position to the pressure exerting position.

The result is a connector that may be positioned easily, locked into good contact and released and removed readily without damage to the associated apparatus or distortion of the contacting members.

Other and further advantages of this invention will be apparent as the description thereof progresses, reference being had to the accompanying drawings, wherein:

Fig. 1 is a top view of the jack;

Fig. 2 is a bottom view of the plug of the connector;

Fig. 3 is an end view of the jack as seen from the bottom of Fig. 1;

Fig. 4 is a section taken along the line 4—4 of Fig. 1;

Fig. 5 is an end view of the plug as seen from the bottom of Fig. 2;

Fig. 6 is a sectional view of the plug of the connector taken along the line 6—6 of Fig. 2;

2

Fig. 7 is a sectional view through the jack and plug of the connector when joined but not locked; and

Fig. 8 is a sectional view through the jack and plug of the connector when joined and locked.

In Fig. 1, the jack as a whole is represented by the numeral 10. This comprises a supporting structure 11 in which is mounted a plurality of conductive contacting members 12 made of a resilient conductive material, such as beryllium copper, and each formed with a connecting lug 13 projecting beyond the mounting structure 11 to which the circuit wires (not shown) are connected. These contacting members 12 are held in place by a back plate 14. A cam shaft 15 is mounted along the main axis of the supporting structure 11 between the two rows of contacting members 12. This shaft 15 protrudes beyond the structure 11 at one end where it is fitted with a handle which may be, as shown in Fig. 1, a section of rod 16 pivotally attached to the shaft 15 by a pin 17. The shaft 15 is fitted with a sleeve 18 of bakelite or other insulating material shaped to a cam profile having a minimum diameter insufficient to exert pressure on the contacting members 12 and a maximum diameter sufficient to exert pressure on the members 12 and give them a certain lateral displacement. The points 20 of minimum diameter of the shaft 15 are brought nearest the members 12 when the shaft 15 is in the released position. The points of maximum diameter 21 are in contact with the members 12 when the shaft 15 is in the lock position. One end 22 of the shaft 15 is formed with the same cam profile as the sleeve 18 but need not be insulated for a purpose to be described later.

The shaft 15 is retained in either the release or lock position against accidental jarring by means of a spring detent (best shown in Fig. 7) comprising a leaf spring 23 mounted on a plate 24 attached to the bottom of the structure 11. This leaf spring 23 urges upward a pin 25 slidably mounted in a hole 26 in the structure 11. This pin 25 urges upward a ball 27 into contact with the cam surface 22 that has a depression 28 at the maximum diameter point 21 and another depression 30 at the minimum diameter point 20. Thus the shaft 15 can be easily moved from one position to the other and when in one position or the other will be retained there against jars. The handle 16 may be provided with a similar detent (not shown) to retain it either coaxial with the shaft 15 when not in use or at right angles to the axis of the shaft 15 when in use.

In Fig. 2, the numeral 31 generally designates the plug portion of the connector comprising a supporting structure 32 in which are mounted contacting elements 33 made of resilient conductive material, such as beryllium copper, arranged in two parallel rows equidistant from the axis of the structure 32 so that, when the plug 31 and the jack 10 are brought together, the contacting elements 33 will be symmetrically arranged on either side of the cam shaft 15. At either end of the row of contact elements 33, there is mounted a locking device 34 formed with a slot having an opening 35 as large as the minimum diameter of the cam shaft 15 and an interior width equal to the maximum diameter of the cam shaft 15. The opening 34 thus forms a latch with a lip 36 under which the uninsulated portion 22 of the shaft 15 is caught to lock the two parts of the connector securely together. This will be best seen by reference to Figs. 7 and 8.

A gasket 37 lines the inner wall of the supporting structure 32 of the plug and protrudes from it to form a water-tight seal when the plug and jack are joined. The connector elements 33 are each formed with a crimp 38 upon which they are supported on a plate 40 of insulating material in which they penetrate by means of slots 41 into a space 42 formed by a lower box 43 of insulating material where they provide lugs to which the circuit wires may be connected after passing through an opening in a collar 44.

Fig. 7 shows the plug 10 inserted into the jack 31 with the shaft 15 in the release position. It will be seen that the connecting elements 12 of the plug 10 have been inserted between the corresponding connecting elements 33 of the jack 31. However, as the portion 20 of the cam surface 18 having the least diameter is positioned in contact with the connecting elements 12, these elements are permitted to lie close together and exert minimum pressure upon the connecting elements 33 of the jack. It will also be seen that the portion 22 of the shaft 15 lies within the opening 35 in the locking device 34 of the jack 31 and so is in a position as to be easily withdrawn.

However, in Fig. 8, the shaft 15 has been rotated ninety degrees so that the cam surfaces 21 of maximum diameter are presented to the connecting elements 12 of the plug 10 and have forced these elements and their associated connecting elements 33 on the jack outward so as to exert maximum contact pressure. It will also be seen that the cam surface 22 is now caught under the projection 36 of the locking device 34 so that the plug 10 is pulled tightly down within the jack 31.

To assure proper alignment, alignment pins 45 are provided on the jack 31. These pins fit into holes 46 on the plug 10.

When it is desired to disconnect the connector, the shaft 15 is rotated into the release position by the handle 16 which releases the pressure on the contact elements 12 and 33 of the plug 31 and jack 10, respectively, and presents the narrow dimension of the cam surface 22 to the opening 35 in the locking device 34 so that the plug may be removed from the jack with the application of a minimum of force.

This invention is not limited to the particular details of construction, materials and processes described, as many equivalents will suggest themselves to those skilled in the art. It is accordingly desired that the appended claims be given

a broad interpretation commensurate with the scope of the invention within the art.

What is claimed is:

1. In an electrical connector, a first group of resilient contact members mounted in a first supporting structure in two parallel rows, a cam shaft mounted parallel to and between the rows of the contact members, said cam shaft having a cross section with portions of a large diameter and other portions of a small diameter, the portion of small diameter fitting freely between the rows of contact members, the portion of large diameter when adjacent to the rows of contact members forcing them outward, a second group of resilient contact members mounted in a second supporting structure in two parallel rows and so spaced that when the supporting structures are brought together with the cam shaft presenting a surface of small diameter to the second group of contact members, these members are

in loose contact with the outer surface of the first group of contact elements and symmetrically arranged about the cam shaft so that when the shaft is positioned to present a surface of major diameter to the contacts they are forced into tight contact, and latch means under control of said cam shaft for locking the supporting structures together.

2. In an electrical connector, a first group of resilient contact members mounted in a first supporting structure in two parallel rows, a cam shaft mounted parallel to and between the rows of the contact members, said cam shaft having a cross section with portions of a large diameter and other portions of a small diameter, the portion of small diameter fitting freely between the rows of contact members, the portion of large diameter when adjacent to the rows of contact members forcing them outward, a second group of resilient contact members mounted in a second supporting structure in two parallel rows and so spaced that when the supporting structures are brought together with the cam shaft presenting a surface of small diameter to the second group of contact members, these members are in loose contact with the outer surface of the first group of contact elements and symmetrically arranged about the cam shaft so that when the shaft is positioned to present a surface of major diameter to the contacts they are forced into tight contact, and latch means under control of said cam shaft for locking the supporting structures together.

3. In an electrical connector, a first group of resilient contact members mounted in a first supporting structure in two parallel rows, a cam shaft mounted parallel to and between the rows of the contact members, said cam shaft having a cross section with portions of a large diameter and other portions of a small diameter, the portion of small diameter fitting freely between the rows of contact members, the portion of large diameter when adjacent to the rows of contact members forcing them outward, a second group of resilient contact members mounted in a second supporting structure in two parallel rows and so spaced that when the supporting structures are brought together with the cam shaft presenting a surface of small diameter to the second group of contact members, these members are in loose contact with the outer surface of the first group of contact elements and symmetrically arranged about the cam shaft so that when the shaft is positioned to present a surface of major diameter to the contacts they are forced into tight contact, and latch means comprising a notched member mounted on an end of the supporting structure for the second group of contacts, the notch formed to readily permit the entrance of the cam shaft with its narrow diameter across the opening and retain the said cam shaft when turned to present the major diameter across the opening.

4. In an electrical connector, a first group of resilient contact members mounted in a first supporting structure in two parallel rows, a cam shaft mounted parallel to and between the rows of the contact members, said cam shaft having a cross section with portions of a large diameter and other portions of a small diameter, the portion of small diameter fitting freely between the rows of contact members, the portion of large diameter when adjacent to the rows of contact members forcing them outward, a second group of resilient contact members mounted in a second supporting structure in two parallel rows and so spaced that, when the supporting structures are brought together with the cam shaft presenting a surface of small diameter to the second group of contact members, these members are in loose

contact with the outer surface of the first group of contact elements and symmetrically arranged about the cam shaft so that, when the shaft is positioned to present a surface of major diameter to the contacts, they are forced into tight contact, and latch means mounted on the supporting structure for the second group of contact members adapted to engage the cam shaft to lock the supporting structure together.
